UNITED STATES PATENT OFFICE.

HANS J. BENTSON, OF WINTHROP HARBOR, ILLINOIS, ASSIGNOR TO FREDERICK C. AUSTIN, OF CHICAGO, ILLINOIS.

DRAG-LINE EXCAVATOR.

1,035,768.

Specification of Letters Patent. Patented Aug. 13, 1912.

Application filed July 26, 1909. Serial No. 509,738.

To all whom it may concern:

Be it known that I, HANS J. BENTSON, a citizen of the United States of America, and resident of Winthrop Harbor, Lake 5 county, Illinois, have invented a certain new and useful Improvement in Drag-Line Excavators, of which the following is a specification.

My invention relates to excavators of that 10 type in which a bucket or scoop is operated by a drag line. In excavators of this kind, as heretofore constructed, the bucket has been free to swing sidewise, or to tip over sidewise, during its travel along the ground. 15 The bucket was pulled forward by the drag line, but there was nothing to prevent it from swaying from side to side and careening over to one side. Consequently, drag line excavators, as heretofore constructed, 20 were not adapted for certain kinds of work. For example, they were not adapted for trenching. Also, and by reason of the fact that the bucket was free to swing sidewise, to some extent, its operation for ordinary 25 purposes was often not efficient or satisfactory. With my improved construction, however, the drag line bucket is guided in a straight line, and held firmly against side straight line, and held firmly against side swing, so that it may be used for trenching. 30 Also, it is held against tipping sidewise, and the bottom of the cut or trench is always level. It is provided with side cutters, whereby it may operate in a trench with sufficient clearance at each side thereof. 35 And in addition the boom of the excavator is provided with means for controlling the bucket to dump the load. Thus in an excavator characterized by my invention the bucket is not only capable of doing the work 40 ordinarily assigned to a drag line excavator in a better and more efficient manner, but is also capable of doing work heretofore considered impossible, or at least impracticable, with a drag line excavator.

45 In the accompanying drawings—Figure 1 is a side elevation of the forward portion of a drag line excavator embodying the principles of my invention. Fig. 2 is a similar view of the rear portion of the same excavator. Fig. 3 is an enlarged side elevation of the bucket in operative position. Fig. 4 is a similar view showing the bucket in dumping position. Fig. 5 is a plan of the drag line bucket showing the preceding

views. Fig. 6 is an enlarged section on line 55 6-6 in Fig. 1.

As thus illustrated, my invention comprises a body A supported on wheels a and provided at its forward end with a turn table or swinging circle B. Upon this revolving member B is mounted a boom C which is provided with a drag line bucket D supported by a hoist-line E running over suitably mounted sheaves. The said bucket is operated by a drag-line F, and the boom 65 C is raised and lowered by a rope or chain G having a connection with a frame H on the body. These ropes or cables are all operated by suitable means on the body, as, for example, the power operated drums I. 70 Similar means may be used for operating the turn table B to swing the bucket from one side to the other.

The bucket is guided or held to a straight line of travel by a pair of beams J which 75 have their lower ends pivoted to the bucket at j, and which are arranged to slide in pivoted guides j' on the boom. In this way the bucket must move forward in a straight line, when the drag-line is operated. Also, 80 it cannot tip over sidewise. Hence it can be used for trenching, and the bottom of the trench will always be level. The bucket has side cutters d, whereby it cuts a trench 85 wider than itself, insuring clearance at each side thereof. It has a lip or cutting edge d' that digs up the load. When the bucket is raised, a wheel K strikes the track d² on the bucket to upset the same and dump the load. (See Fig. 4). This wheel K is 90 mounted at the lower end of an arm k that has holes k' for moving or adjusting the operative portion thereof on the boom. Then the wheel can be adjusted up and down to get the right dumping action. Thus means 95 are provided on the boom for engaging the bucket to dump the load—that is to say, a connection is provided between the boom and bucket to control it when raised. However, this may be done in various ways, if 100 desired.

From the foregoing it will be seen that I provide novel improvements whereby a drag-line excavator is not only rendered more certain in operation for ordinary 105 work, as the bucket is held in position to fill more readily, and kept moving in a straight line, but also whereby certain other

kinds of work are made possible with an excavator of this type.

I do not, therefore, limit myself to the exact construction shown and described.

5. What I claim as my invention is:

1. In an excavator, a bucket, a drag-line therefor, a boom, guide beams for the bucket, to keep the bucket moving in a straight line while filling, a pivotal connection between said bucket and beams, and a wheel on the boom for engaging the bucket to tilt the same about its said pivotal connection and thereby dump the load.

10. 2. In an excavator, a bucket, a drag-line therefor, a boom, guide beams for the bucket, which beams keep the bucket to a straight line of travel, a pivotal connection between said beams and bucket, and means on the boom for engaging the bucket to tilt 15 the same about said pivotal connection and thereby dump the load.

20. 3. In an excavator, a bucket, a drag-line therefor, means for operating the drag-line to cause the bucket to fill by movement to cause the bucket to fill by movement

thereof toward the excavator, a boom, guide beams for the bucket, to keep the bucket moving in a straight line while filling, a pivotal connection between said bucket and beams, and a wheel on the boom for engaging the bucket to tilt the same about its said pivotal connection and thereby dump the load.

4. In an excavator, a bucket, a drag-line therefor, means for operating the drag-line to cause the bucket to fill by movement 35 thereof toward the excavator, a boom, guide beams for the bucket, a pivotal connection between said beams and bucket, and means on the boom for engaging the bucket to tilt the same about said pivotal connection and thereby dump the load.

Signed by me at Chicago, Ill., this 2nd day of July 1909.

HANS J. BENTSON.
